(57) **CLAIM**

We claim the ornamental design for a display screen or portion thereof with a graphical user interface, as shown and described.

DESCRIPTION

FIG. 1 is a front view of a first embodiment for a display screen or portion thereof with a graphical user interface showing our new design;

FIG. 2 is a front view of a second embodiment thereof; and, FIG. 3 is a front view of a third embodiment thereof.

The outermost broken line rectangle shows the display screen or portion thereof. All other broken lines show portions of the graphical user interface and form no part of the claimed design.
